STOP MOTION APPARATUS FOR WRAPPING MACHINES

Jocie C. Barefoot, Charlotte, N. C.

Application June 1, 1949, Serial No. 96,505

5 Claims. (Cl. 53—29)

1

This invention relates to a machine for wrapping cakes, cookies and the like, and more specifically it relates to an improved automatic stop motion apparatus for such machines.

The present invention is particularly concerned with a control system for that type of wrapping machine which has a driven feed conveyor onto which cakes or the like are adapted to be placed for delivery to a wrapping station at which a wrapping sheet is presented. In such machines the cakes are automatically removed from the conveyor by a transfer device which moves the cake into engagement with a sheet of wrapping material, such as cellophane, which is automatically fed in sheets of predetermined size to a wrapping station above the path of the feed conveyor. Means are provided in such machines for further folding the wrapping sheet about the cake and for then feeding the package into contact with heated surfaces which seal the wrapping material to form a closed package. The wrapped cakes or the like are then delivered from the machine ready for further packaging and distribution.

Although it is to be understood that the present invention may be applied with equal ease to many other types of machines, the present invention is shown as being applied to a machine of the type manufactured by Battle Creek Bread Wrapping Machine Company, Battle Creek, Michigan, known as their Model 34 machine.

Heretofore machines of this general type have been provided with stop motion mechanism effective to stop the feed of wrapping material in the event a cake is not positioned on the feed conveyor for transfer into engagement with a lower surface of a wrapping sheet at the wrapping station. Such controls have prevented the delivery of unneeded wrapping material to the wrapping station.

However, in known control systems, a cake presented at the wrapping station in the absence of wrapping material may be raised by the transfer means and will thereby be passed through the machine without being wrapped. It is manifest that this results in the various parts of the machine becoming coated with filling material or frosting which is usually on cakes of this type, and cakes so delivered are also broken into small pieces as they pass through the wrapping mechanism. This necessitates that damaged and broken cakes be removed from the machine and be thrown away, and it also requires that the machine be stopped and cleaned before further operation.

2

It is, therefore, an object of this invention to provide automatic means for immediately stopping the machine in the event a sheet of cake wrapping material is not disposed above the cake transfer device, although the cake may be positioned on the conveyor for engagement by such device.

It is another object of this invention to provide automatic stop motion means for cake wrapping machines of the type described which will be rendered operative for stopping the machine upon absence of a sheet of wrapping material at the wrapping station above the elevating means, although the elevating means may engage a cake or the like on the conveyor.

It is a further object to provide means whereby the cake elevating mechanism may continue to operate for a predetermined length of time for elevating the cake to a position above the point at which it normally engages the wrapping material and to thereby position the cake where it will be accessible for removal after the machine has stopped.

It is still another object of this invention to provide a brake mechanism adapted to cooperate with the stop motion apparatus, which is automatically rendered operable in timed relation to the cake conveying apparatus and elevating means upon failure in delivery of a piece of wrapping material in the wrapping station above the elevating means, and to thus stop the machine when the elevating means is at its maximum elevation, thereby enabling an operator to remove the cake from the machine with the least possible inconvenience.

Some of the objects of the invention have been stated hereinabove, but other objects will appear as the description is read in connection with the accompanying drawings in which:

40 Figure 1 is a plan view of the cake wrapping machine showing the control system applied thereto;

Fig. 2 is a vertical sectional view through the cake wrapping machine taken on line 2—2 of Fig. 1;

Fig. 3 is an enlarged elevational view on line 3—3 of Fig. 1, some parts being shown in section and others in full line;

Fig. 4 is an enlarged fragmentary elevational view on line 4—4 of Fig. 1 with some parts thereof in section and other parts thereof omitted;

Fig. 5 is an elevational view on line 5—5 of Fig. 4, showing a part of the stop motion mechanism;

3

Fig. 6 is a vertical sectional view on line 6—6 of Fig. 4, showing the brake mechanism;

Fig. 7 is a view similar to Fig. 6 but shows the parts in a displaced position relative thereto;

Fig. 8 is an enlarged sectional view taken on line 8-8 of Fig. 1, and shows the web cutting and sheet delivery mechanism;

Fig. 9 is a more or less schematic view generally along line 9—9 of Fig. 8, showing a power transmission control device;

Fig. 10 is an elevational view taken on line 10-10 of Fig. 1, omitting the folding and ejecting mechanism relative to the wrapping station and showing part of the improved stop mechanism as applied to the wrapping machine;

Fig. 11 is an enlarged vertical sectional view through a vacuum switch taken on line 11-11 of Fig. 10;

Fig. 12 is an enlarged schematic vertical sectional view taken on line 12—12 of Fig. 8, showing part of the wrapping station;

Fig. 13 is an enlarged vertical sectional view taken on line 13-13 of Fig. 3, showing a time delay relay mechanism adapted for use in the control system;

Fig. 14 is an enlarged elevational view taken on line 14-14 of Fig. 5, showing a clutch releasing mechanism which is responsive to the improved stop motion mechanism herein;

Fig. 15 is a vertical sectional view on line 15—15 of Fig. 4, showing the brake mechanism and also showing power transmission clutch mechanism;

Fig. 16 is an enlarged vertical sectional view taken on line 16—16 of Fig. 10; and

Fig. 17 is a schematic diagram showing electrically and pneumatically operated devices comprising the improved stop motion system.

The wrapping machine frame 10 comprises side frame members 11 and 12 which are joined together at one end by cross frame members 13 and 14 and at the other end by cross frame members 15 and 16. For the purpose of this description, the left hand or feed end of the machine, as viewed in Figs. 1 and 2, will hereinafter be referred to as the front of the machine, while the right hand or discharge end of the machine as viewed in the same figures will be referred to as the rear of the machine.

Conveyor frame members 20 and 21 are suitably secured at one end to the cross frame member 16 and at the opposite end they are supported on suitable stands 23, only one of which is illustrated in Fig. 2. The side frame members 11 and 12 and the conveyor stands 23 are adapted for support on any suitable base such as a floor. Means for feeding and cutting a web of wrapping material is supported on spaced frame members 25 and 26 which are suitably secured to the side frame member 11 of the machine chassis.

The machine is adapted to be driven by an electric motor 30 (Fig. 10) which by its leads 31 and 32 is adapted for inclusion in a control system which is to be described more particularly hereinafter. The electric motor 30 is suitably secured to a motor bracket 33, the bracket being secured as by screws 34 to the cross frame member 13. The motor has a driven pulley 35 thereon which is mounted a wide V-belt 36. The V-belt 36 extends to an idler pulley 37 (Fig. 4) mounted for rotation on a drive shaft 40. The pulley 37 has a dog clutch member 42 formed integrally therewith (Fig. 15) which is adapted to engage a mating dog clutch member 43 splined on the drive shaft 40 by means of splines 44 for

4

limited longitudinal sliding movement on the drive shaft 40.

The dog clutch member 43 has an annular groove 45 therein which is adapted for engagement with one end of a yoke member 46 which is fixed at its other end on a shipper shaft 50. The drive shaft 40 is journaled for rotation in the side frame members 11 and 12, and the shipper shaft 50 is mounted for longitudinal sliding movement in the side frame members 11 and 12. Means has been provided herein for automatically operating the shipper shaft 50 for disengaging the dog clutch members 42 and 43, and since this mechanism is an important part of the present invention, it will be described in greater detail at a later point herein.

The drive shaft 40 extends beyond the side frame member 11 (Fig. 15) and has fixed thereto a hand wheel 51. The other end of the drive shaft 40 extends beyond the opposite side frame member 12 and has another hand wheel 52 (Fig. 10) fixed to the end thereof. A pinion 53 is mounted on the drive shaft 40 for rotation therewith at a point intermediate its ends (Fig. 2). The pinion 52 meshes with a gear 54 which is keyed to a cam shaft 55, the latter being journaled for rotation in the side frame members 11 and 12.

A miter gear 56 fixed to shaft 55 adjacent the side frame member 11 (Fig. 10) meshes with a miter gear 57 fixed to one end of a forwardly and rearwardly extending shaft 60. The shaft 60 is mounted for rotation in suitable bearings 61 which are secured to the side frame member 11. The opposite end of the shaft 60 likewise has a miter gear 62 fixed thereto, and this miter gear meshes with a second miter gear 63 fixed to a cam shaft 65, which in turn is journaled for rotation in the side frame members 11 and 12.

By reference to Fig. 2 it may be observed that the cam shaft 65 has a sprocket wheel 66 keyed thereto, and that the sprocket wheel 66 engages a sprocket chain 67. The sprocket chain 67 is in driving engagement with a sprocket wheel 70 which is keyed to an idler shaft 71 journaled for rotation in the side frame members 11 and 12. The shaft 71 has a plurality of sprocket wheels 72 keyed thereto, only one of which is shown in Fig. 2. The sprocket wheels 72 are spaced from each other and support sprocket chains 73-76, inclusive. Portions of the sprocket chains 73-76, inclusive, are shown at the feed end of the machine in Fig. 1. The sprocket conveyor chains 73 and 74 are also shown in Fig. 2. The sprocket conveyor chains 75 and 76 are mounted in the same manner as the sprocket conveyor chains 73 and 74, respectively, therefore, a consideration of the mounting of the sprocket chain 74 as shown in Fig. 2 will indicate the manner in which

the remaining chains of this series are mounted. The chain 74 extends downwardly from the sprocket wheel 71 and passes under an idler sprocket wheel 80 from which point it assumes a generally horizontal course where it passes beneath another idler sprocket wheel 81. The idler sprocket wheels 80 and 81 are keyed to transverse shafts 82 and 83 respectively, both of which are rotatably journaled in the side frame members 11 and 12. It will be noted that the conveyor sprocket chain 74 extends upwardly from the sprocket wheel 81 is a substantially vertical plane and passes over an idler sprocket wheel 85, the idler sprocket wheel 85 being keyed to a transverse shaft 86, which is journaled for free rotation in the conveyor frame members 20 and

24. The conveyor chain 73 assumes a somewhat rearwardly inclined upward course and extends about an idler sprocket wheel 87 located somewhat to the rear of the idler sprocket 85. The sprocket conveyor chains 73 and 74 are trained beneath and around a pair of sprocket wheels 90 and 91, which are keyed to a transverse shaft 92, the latter being journaled for rotation in the conveyor frame members 20 and 21. The upper reaches of the conveyor chains 73-75, inclusive, then extend to the first described set of sprocket wheels 72.

A plurality of alternately spaced angle bars 93 extend between and are connected to the sprocket conveyor chains 73 and 75. Between each of the angle bars 93 is an angle bar 94 which has its opposite ends connected to the sprocket chains 74 and 75 and, as is conventional in wrapping machines of this kind, the shafts 86 and 87 are so mounted that they may be adjusted relative to each other in order to increase or decrease the distance between the complementary sets of angle bars 93 and 94 to accommodate articles of various sizes.

It may be observed in Figs. 1 and 2 that there is a pair of sprocket wheels 100 keyed to the shaft 92 and these sprocket wheels are spaced from each other and accommodate conveyor sprocket chains 101. The remote bight of the conveyor sprocket chain flights engage sprocket wheels 102 which are mounted for rotation on a stub shaft 104 carried by the machine frame at a point between the conveyor frame members 20 and 21. The conveyor sprocket chains 101 are each provided with a plurality of equally spaced guide plates 110, which are effective to prevent endwise movement of the cake or other article disposed on the angle bars 93 and 94. It will be noted in Fig. 2 that each of the cakes or similar articles C is preferably mounted on a suitably shaped pallet D of cardboard or other suitable material. These supporting pallets are usually included in the cake package and contribute to the successful operation of the wrapping machine.

It may be perceived, therefore, how the conveyor comprising conveyor chains 73-75, inclusive, and 101 is constantly driven. Arranged to move in timed relation to the movement of the conveyor chains is an elevating member 115 which is shown in its raised position in Fig. 2 and which is mounted for oscillating movement between its raised and lowered position by means of connections 116 and 117 to operating arms 118 and 119, respectively. The arm 119 is fixed to a shaft 122 which is adapted to rock in suitable brackets secured to the side frame members 11 and 12. The arm 118 is connected for pivotal movement to an arm 123 which is fixed to a transverse shaft 124, the latter being mounted for rocking movement in the side frame members 11 and 12. It will be noted by reference to Fig. 2 that the shaft 124 has a cam following arm 125 fixed to its outer end. The cam following arm is adapted to ride at its free end in a face cam 127 having an irregular groove 128 therein for transmitting oscillating motion to the shaft 124 and thus to the elevating arm 115. The elevating arm 115 has a plate 130 at its upper end which is adapted to engage the lower face of the pallet members D upon which the cakes C rest as they pass above the elevating arm while disposed on the conveyor angle members 93 and 94. It will follow, therefore, that when in such position, oscillation of the elevating arm linkage will transfer the cake C to the raised position as shown in

Fig. 2 and which position may be referred to as the wrapping station.

In its upward movement, the upper portion of the elevating arm 115 passes between horizontally disposed plates 132 and 133 (Figs. 1 and 2) which slidably support the upper reaches of conveyor belts 134 and 135, respectively. The conveyor belts 134 and 135 are designed to carry sheets of wrapping material W from the point at which they are cut from a web to the wrapping station, all as will be described in greater detail hereinafter. The plates 132 and 133 are suitably secured at opposite ends thereof to the side frame members 11 and 12.

The conveyor belts 134 and 135 are mounted in an identical manner and by referring to Fig. 8 it may be observed that the right hand portion of the conveyor belt 135 passes through the plate 133 and is mounted on an idler roll 136. The left hand portion of the belt is mounted on a roller 137 fixed to a shaft 140 which is journaled for rotation in bearing blocks 141. The shaft 140 has a sprocket wheel 142 keyed to one end thereof. A sprocket chain 143 connects the sprocket wheel 142 with a sprocket wheel 145 keyed to the forwardly and rearwardly extending shaft 60 hereinabove described.

As best seen in Figs. 3, 8 and 9, the shaft 60 also has a sprocket wheel 147 free thereon, and forming a part of the sprocket wheel 147 or being attached thereto is a clutch plate 150 on which a clutch pawl 151 is mounted for rocking movement about a stud 152. A tension spring 153 normally urges the clutch pawl 151 into engagement with a tooth 156 projecting from the periphery of a cam wheel 155. The cam wheel 155 is keyed to the shaft 60, and it follows, therefore, that when the clutch pawl 151 is in engagement with the projection 156 of the cam wheel 155, rotation will be transmitted to the sprocket wheel 147 and from the sprocket wheel 147 through the sprocket chain 160, the upper bight of which is in driving contact with a sprocket wheel 161 for driving the web cutting mechanism and the sheet feeding means.

Reference to Figs. 2 and 9 will disclose a finger 163 which is normally urged upwardly into the path of the cake conveyor about a fixed pivot 163a by a weight arm 164. However, as cakes pass over the finger 163, the finger is depressed in a clockwise direction as viewed in Fig. 9, and this movement is effective to impart right to left movement to an arm 165. The arm 165 has a lock segment 166 pivotally connected thereto, and this segment in turn is mounted for rocking movement about a pivot point 167 on a bracket 170 suitably secured to the side frame member 11.

The locking segment 166 is adapted to normally engage the upper surface of an annular shoulder 171 formed in the body of a vertically movable plunger 172 (Fig. 9). The plunger 172 is mounted for free vertical sliding movement in the bracket 170. As its lower end rides in contact with the clutch pawl member 151, the tension of the spring 153 is sufficiently great to overcome the added weight of the plunger 172.

Reference to Fig. 9 will show that the plunger 172 is held in its lower position whenever the finger 163 is free to swing upwardly in the absence of a cake on the conveyor mechanism thereabove. When the plunger is latched against upward movement, the pawl 151 is forced to move in a counterclockwise direction against the tension of the spring 153, thus moving out of engagement with the projection 156 on the cam

wheel 175. This destroys the connection between the sprocket 147 and the shaft 60, thereby permitting the shaft to rotate freely with respect to the sprocket. With the parts in this latter condition, the wrapping material severing and feeding means is disabled.

The sprocket wheel 161 is fixed to a shaft 175, which is mounted for rotation in the frame members 25 and 26. The shaft 175 extends through the frame member 25 where it enters a housing 176 (Fig. 1) in which conventional transmission gearing (not shown) is disposed for driving shafts 180, 181 and 182 in the direction indicated by the arrows in Fig. 8. The shafts 180 and 181 have feed rollers 184 and 185 mounted thereon. The feed rollers receive and feed wrapping material M from a roll R rotatably mounted in the frame members 25 and 26.

The feed rollers 184 and 185 are effective to feed the wrapping material M to a fixed cutter plate 190 (Fig. 8) which extends between and is suitably secured to the frame members 25 and 26. Fixed to the shaft 182 is a blade carrying member 191 having a cutter blade 192 secured thereto as by screws 193. It will be noted by reference to Fig. 8 that the blade 192 is adapted to pass in cutting relation to the fixed cutter plate 190, and when wrapping material M passes therebetween, it is cut into sheets W heretofore mentioned. The sheets of wrapping material are then received by plates 132 and 133 and are delivered to the conveyor belts 134 and 135 for movement into the wrapping station.

It will be noted by reference to Figs. 2, 8 and 12 that upward movement of the elevating arm 115 transfers a cake at the wrapping zone into engagement with the lower face of the wrapping sheet, and this continued movement is effective to elevate the cake and superimposed sheet upwardly between a plate 195 and an angle bar 196 (Fig. 2). The angle bar 196 has ears 197 (Fig. 8) at opposite ends thereof, and these ears support a member 200 for oscillating movement. The member 200 is mounted for oscillation in timed relation to the movement of the elevating means so that it moves out of the path of travel of a cake and its associated supporting pallet as the elevating member 115 transfers the cake upwardly past the same. After passage of the cake, the oscillating member 200 moves into the position shown in Figs. 2 and 12 to engage the lower surface of the supporting pallet D and supports the cake in position for a subsequent operating step.

The plate 195 is mounted for horizontal sliding movement between guide members 210 and 211 (Figs. 1 and 2), and a similar plate 212 is mounted for horizontal slide movement in guide members 210 and 211, the latter being disposed above and in spaced relation to the plate 195 as seen in Fig. 2. An ejecting block 215 is suitably secured to the lower surface of the plate 212 and engages the upper surface of the plate 195 in sliding relation. The plates 195 and 212 are adapted to reciprocate simultaneously in opposite directions relative to each other, although it is to be understood that the plate 212 has a substantially greater stroke than the plate 195, inasmuch as the plate 195 merely moves out of the path of the cake supporting pallet D as it is raised to the wrapping station, and then moves under one edge of the supporting pallet to afford support to that edge of the cake as the elevating member 115 moves downwardly as viewed in Fig. 2. On the other hand, the plate 212 and its associated ejecting block 215 moves from left to right as

viewed in Fig. 2 for ejecting the cake along with its supporting pallet from the wrapping station. In its movement out of the wrapping station, the cake and its associated supporting and wrapping material moves across the upper surface of the angle bar 196 and also moves along conventional folding bars 216 which fold the sheet of wrapping material around the cake in a manner that is well known in the art and need not be described in specific detail herein.

Reference to Figs. 1 and 2 will disclose that conveyor bars 217 extend from the driven conveyor chains 218 and provide a way along which the cakes move through the folding and heat sealing zones of the machine. The conveyor bars 217 discharge the wrapped cake package from the wrapping machine after the cake has been wrapped and sealed as generally described hereinabove.

Reciprocating motion is transmitted to the plates 195 and 212 through oscillating crank arms 225 and 226, respectively. This mechanism may best be seen in Fig. 2 of the drawings. The crank arm 225 is mounted on and fixed to a shaft 227 which is mounted for oscillation in the side frame members 11 and 12, the shaft 227 having a crank arm 230 (Fig. 10) mounted on one end thereof. One end of a connecting rod 231 is pivoted to the downwardly extending end of the crank arm 230. The opposite end of the connecting rod 231 is connected to a bell crank 232 which is mounted for oscillating movement on a stud 233 extending from the side frame member 12. One of the arms of the bell crank 232 has a substantially vertically extending groove 235 in its surface adjacent the side frame member 12, and this groove is adapted to embrace a cam follower 236 which projects from a cam wheel 237 fixed to the end of the shaft 55.

The crank arm 226 is mounted for oscillation on an idler shaft 240 (Fig. 2). The idler shaft is mounted for rocking movement on the side frame members 11 and 12. The crank arm 226 has another arm 241 integral therewith, and the free end of the arm has mounted thereon for pivotal movement a connecting rod 242. The other end of the connecting rod 242 is pivoted to one arm of a bell crank 243 which is mounted for oscillation on a bar 244 on the side frame member 12. The opposite arm of the bell crank 243 is adapted to engage a cam wheel 245 fixed for rotation with the transverse shaft 55. The foregoing structure is, therefore, effective to transmit reciprocating motion to the plates 195 and 212.

By reference to Fig. 15 it will be seen that one end of the shaft 50 is pivotally connected to the upper end of a yoke arm 251, the lower end of which is fixed to the forwardly and rearwardly extending shaft 252 (Figs. 4 and 15). The shaft 252 is mounted for oscillation in bearing blocks 253 and 254 secured by screws 256 to the side frame member 11. Keyed to one end of the shaft 252 (Fig. 4) and extending upwardly therefrom is a shipper handle 260.

Figs. 4, 6, 7 and 15 will disclose a brake mechanism which is effective for halting the movement of the cake conveyor and the wrapping material cutting and feed mechanism upon operation of the stop motion mechanism, in a manner to be described at a later point herein. A block 246 is adjustably secured to the shaft 252 by means of an adjusting screw 246a. The block 246 has a bar 247 secured thereto by screws 248, and the block carries a brake shoe 249, the upper

surface of which is concave. Suitable friction brake material 249a is riveted to the brake shoe 249. It will be noted in Figs. 6 and 7 that the brake lining material 249a is adapted to engage the periphery of the hand wheel 51 for stopping the machine instantaneously upon operation of the stop mechanism.

It will be observed by reference to Figs. 1 and 5 that the shipper handle 260 carries a projection 261 intermediate its ends, and to this projection is attached one end of a sprocket chain 264 which extends horizontally for a short distance where it passes over a roller 262, the opposite flight of the chain extending downwardly and being connected to the upper end of a shaft 264. The shaft 264 is guided for sliding movement in a sleeve 265 which is welded to the upper surface of a plate 266, the plate 266 constituting a part of a weight housing and being provided with a passage for the shaft 264. The weight housing 267 may be seen in Figs. 1, 4, 5 and 14 of the drawings.

The plate 266 is welded at opposite ends thereof to vertically disposed housing plates 270 and 271, the lower ends of which are welded to angle bars 272 and 273, respectively. The angle bars may be secured to the general supporting surface by means of screws 275. Extending between the vertical plate 270 and 271 and welded to edges thereof are plates 276, 277 and 278, which together constitute the weight housing 267. A clutch and brake operating weight 281 are mounted for movement in the weight housing 267, the same being fixed as by threading to the lower end of the shaft 264. Welded to the upper surface of the plate 266 of the weight housing 267 and extending upwardly therefrom is a standard 282, the upper end of which supports a stub shaft 283 on which the roller 263 is rotatably supported.

The sleeve 265, as best seen in Fig. 14, has a slot 284 extending through the wall thereof and the shaft 264 has an annular groove therein. The slot 285 permits a slide member 287 to pass therethrough for engaging a wall of the annular groove 286 in the shaft 264. The slide member 287 is mounted for horizontal sliding movement in guide blocks 290 secured as by welding to the upper surface of the plate 266 of the weight housing 257.

The outer end of the slide member 287 (Fig. 14) is connected to a curved pin 291 projecting from a metallic lever arm 292 mounted for rocking movement about point 293 on a supporting arm 294. The supporting arm 294 is secured by screws 295 to a substantially U-shaped electromagnet core member 296. One of the legs of the U-shaped core member 296 extends through an induction coil 300 wound thereabout, the coil being adapted for energization through conductors 301 and 302. The conductor 301 (Fig. 17) extends to a vacuum switch 305 and the conductor 302 extends to a delay relay switch 306.

The vacuum switch 305 comprises a switch housing 307 having stationary contacts 308 and 309 therein. The conductor 301 is electrically connected to the contact 308. The contact 309 anchors one end of a conductor 312 which extends therefrom (Figs. 11 and 17) and has its other end electrically connected to a lead conductor 313. The lead conductor 313 includes within its length a master switch 314, and the end thereof beyond the master switch is fixed to one terminal of an electrical connector 315 which is adapted to be plugged into a suitable source of electric

energy, not shown. The other terminal of the male plug 315 is connected through suitable conductors with other parts of the control mechanism to be described later. The control circuit includes a lead wire 317, and it may be noted by reference to Fig. 17 that the leads 31 and 32 from the electric motor 30 are connected to the conductors 313 and 317, respectively. Thus, the electric motor is controlled by the master switch 314 and is energized upon closure of that switch.

The vacuum switch housing 307 is secured to one end of a bracket 320 secured by screws 321 to the side frame member 12. The housing 301 of the vacuum switch has a plunger 322 mounted therein for vertical sliding movement. The upper end of the plunger 322 projects through the switch housing and extends upwardly therefrom. The lower end of the plunger 322 is connected to a metallic cross arm 323 having at its ends contact members 324 and 325 which are adapted to engage the fixed contact members 308 and 309, respectively. A compression spring 321 urges the plunger and its cross bar 323 upwardly, the lower end of the spring bearing against, but being insulated from, an inverted cup-shaped member 330 secured as by screws 331 to the bottom of the switch housing 307.

The inverted cup-shaped member 330 is flanged at its peripheral edge and secured as by screws 332 to the flanged peripheral edge of a complementary cup-shaped member 333. The cup-shaped members are hermetically attached to each other at their flanged edges and support therebetween a diaphragm 334, thereby providing a sealed chamber wherein the diaphragm is sensitive to variations in fluid pressures within the lower diaphragm chamber. The diaphragm 334 is penetrated by a stud 336 which extends upwardly and is slidably guided for reciprocating movement in the inverted cup-shaped member 330. The upper end of the stud 336 is welded to an inverted L-shaped switch actuating member 337, the horizontally disposed leg of which engages the upper end of the switch plunger 322 which is urged against the horizontal leg of the actuator by the compression spring 321.

The bottom of the cup-shaped member 333 is penetrated by a nipple 340 which is hermetically secured thereto as by welding, and which is adapted to receive one end of a flexible tube 341. The tube 341 has its remote end connected to a T conduit 342. Another branch of the T conduit 342 has secured thereto a flexible tube 344 which is in communication with a nipple 345 of a diaphragm pump 346, the details and function of which will be described at a later point. The third leg of the T connection 342 is in communication with one end of a conduit 350, the other end of which communicates with the lower end of a threaded tube 351 constituting a wrapping sheet sensing device. The connections between the several nipples and tubes are preferably adhesively achieved to render them airtight.

It will be noted by reference to Fig. 12 that the upper end of the threaded tube 351 has formed at its free end a flange 352 which is substantially as thick as the conveyor belts 134 and 135 so that sheets of wrapping material being conveyed by the belts 134 and 135 will engage and close the upper end of the sensing nipple 351. The sensing nipple 351 is accommodated by a passage in the plate 133 and is provided with a lock nut 354 threaded thereon to engage

11

the lower surface of the plate 133, thus securing the nipple 351 to the plate 133.

It will be noted by reference to Fig. 12 that the sensing nipple 351 is positioned adjacent the conveyor belt 135 and thus occupies an off-center position relative to the normal path of travel of the wrapping sheet material W. In this position the sensing nipple is effective to permit energization of the stop motion mechanism in the event the sheets of wrapping material are not positioned with their side edges parallel to the path of travel of the conveyor belts 134 and 135. It will become apparent that the open end of the sensing nipple 351 must be closed by a sheet of wrapping material at specified times in the operating cycle if the operation of the machine is to proceed uninterrupted.

The fluid pressure pump 346 comprises a cast inverted cup-shaped member 355 whose peripheral edge is flanged outwardly to provide a surface at which the same is secured as by screws 356 to the flanged peripheral edge of a cup-shaped member 357. The cup-shaped member 357 is penetrated by the nipple 345, the nipple being secured thereto as by welding. The lower cup-shaped member is supported by an angle bracket 360 to which it is secured by a bolt 361. The bracket 361 is secured by bolts 362 to the side frame member 12. The upper cup-shaped member 355 has a horizontal partition 363 through which passes a shaft 364, the lower end of which passes through a diaphragm member 365 hermetically secured at its periphery between the upper and lower cup-shaped members 355 and 357, respectively. The lower end of the shaft 364 is threaded and receives lock nuts 366 and 367 which engage the upper and lower surfaces of the diaphragm member so that movement of the shaft 364 will be transmitted to the diaphragm. The upper end of the shaft 364 (Figs. 16 and 17) has an enlarged portion 370 integral therewith. A compression spring 371 is mounted between the lower face of the enlarged portion 370 and the upper surface of the partition 363, thus normally urging the shaft 364 upwardly. The enlarged portion 370 of the shaft 364 is pivoted to one end of a lever arm 372, the lever arm 372 being mounted for rocking movement about a pivot stud 373 supported in the side walls of the inverted cup-shaped member. The inverted cup-shaped member 355 has a passage 374 in one side thereof, through which the lever arm 372 extends. The free end of the lever arm 372 has a roller 375 rotatably mounted thereon, the same being adapted to engage the periphery of a cam wheel 377 which may be an integral part of the face cam 327 heretofore described. The cam 377 may, on the other hand, be separately provided and fixed for rotation on the shaft 65.

The cam wheel 377 has a peripheral notch 380 into which the cam follower roller 375 is urged by the compression spring 371 when the notch rotates into the zone of the roller. As the compression spring 371 forces the roller 375 downwardly into the cam notch 380, it is manifest that the diaphragm 365 will be moved upwardly and, in so doing, will create a negative pressure in the conduit 344. Assuming that a sheet of wrapping material W is in overlying position with relation to the open end of the sensing nipple 351, the suction thus created in the conduit 344 will create a suction in the conduit 341 and in the lower cup-shaped member 333 of the vacuum switch 305. The diaphragm 334 of the vacuum switch 305 will then be urged downwardly by the greater

12

atmospheric pressure on the upper face thereof, and this in turn will result in downward movement of the stud 336 and the accompanying movement of the contact bar 332 and its associated contacts 324 and 325 out of engagement with the contact members 308 and 309, thus opening the circuit through the vacuum switch 305. Conversely, therefore, when no wrapping material overlies the open end of the sensing nipple 351, the negative pressure created in the conduit 334 will draw air through the sensing nipple and the connecting pipe 350, thus leaving unaffected the diaphragm 334 in the vacuum switch 305. Under these conditions the circuit through the vacuum switch 305 will remain closed.

The conductor 302 which extends from the magnetic coil 300 associated with the weight release mechanism shown in Fig. 14 extends to the time delay relay 306. There are several types of time delay relays which may be used for the purpose of the control system herein, and the specific mechanism disclosed in Fig. 13 of the drawing may therefore be considered as representative of a number of conventional devices that are available. The relay 306 is supported by a base plate 382 secured by screws 383 to the frame member 26. A block 395 is suitably secured to the plate 382 and has a solenoid coil 386 suitably secured thereto. The solenoid 386 has associated therewith a core 387 mounted for vertical sliding movement therein. The free end of the core is connected as at 390 to a slide member 391 mounted for vertical sliding movement in a guide frame 392 which is integral with the block 385. The slide member 391 carries a Z-shaped operating plate 393 to which one end of a tension spring 394 is connected. The other end of the tension spring 394 is connected to a diaphragm valve housing 395 which likewise is secured to a supporting plate 382. It may be understood, therefore, that the tension spring 394 normally urges the slide member 391 upwardly, as best seen in Fig. 13. The vacuum valve housing 395 has a pin 396 projecting downwardly therefrom for guiding the reciprocation of a block of insulating material 397. The block 397 is urged against the Z-shaped plate 393 by a compression spring 400 which bears against the lower surface of the diaphragm valve housing 395. The block 397 has pivoted thereto one end of a lever arm 401 which is mounted for rocking movement intermediate its ends about an ear 403 which projects from the valve housing 395. A switch housing 405 is secured to the ear 403 and its upper wall has a passage therethrough which serves as a guide for a sliding switch plunger 406. The free end of the switch plunger 406 engages an adjusting screw 407 threaded in the lever arm 401. The plunger 406 is of insulating material and supports at its lower end a leaf spring contact bar 410 which has contact members 411 and 412 secured at opposite ends thereof.

As schematically shown in Fig. 17, the switch housing 405 has therein fixed contact members 413 and 414 which are adapted to be engaged by the movable contact members 411 and 412, respectively. A suitable compression spring 415 engages the lower surface of the leaf spring contact bar 410 and bears against the lower wall of the housing 405, thereby urging the leaf spring contact bar 410 and its associated plunger 406 upwardly. The lead 302 from the solenoid 300 extends to and is connected with the contact member 413. The contact member 414 has a conductor 420 extending therefrom, the other end of

which is electrically connected to a leaf spring contact bar 421 disposed within a switch housing 422, to be described more specifically hereinafter.

Housing 395 of the relay delay mechanism 396 has a cavity 424 therein which is spanned by a diaphragm 425 to the center of which one end of an L-shaped member 426 is suitably connected. One leg of the L-shaped member 426 extends downwardly through the lower wall of the housing 395 and is secured at its lower end to the insulating block 397. The diaphragm member 425 is secured to the upper edge of the housing 395 by a block member 427 having a cavity 430 therein, the block member 427 being secured to the housing 395 by screws 432.

The block member 427 has a suitable needle valve mechanism 433 which is adjustable to permit passage of air into the chamber 430, there being a suitable exhaust valve mechanism 435 mounted in the upper wall of the block 427 through which the air in the chamber 430 may escape when the tension spring 394 urges upwardly the Z-shaped plate 393, its associated block 397, the L-shaped member 426, and the diaphragm 425. It is to be understood that the tension spring 394 is substantially stronger than the compression spring 400 so that the compression spring offers negligible resistance to the tension spring as it moves the associated parts upwardly as hereinabove described.

The solenoid coil 386 is energized through conductors 440 and 441, the conductor 441 being connected to a conductor 442, one end of which is connected to the lead conductor 317 and the other end of which is connected to a fixed contact bar 444 which is a part of the switch mechanism 422 hereinbefore mentioned. It may be observed, particularly with reference to Fig. 3, that the switch 422 is secured as by screws 446 to a bracket 447, the lower end of which is secured as by screws 448 to a conventional chain guard 452 extending over the sprocket chain 160 and the sprocket wheel 161, and being suitably secured to the frame member 26.

The switch 422 has a plunger 453 mounted for horizontal sliding movement therein, the inner end of the plunger engaging a leaf spring contact member 421. The plunger 453 is of insulating material, and its outer end engages an operating lever 454. The upper end of the lever 454 is pivoted on a stud 455, and the lower free end thereof rotatably mounts a cam following roller 457. The roller 457 is adapted to engage the periphery of a cam wheel 460 having a lobe or projection 461 thereon. The cam wheel is fixed for rotation on one end of the shaft 182 on which the web blade carrying member 191 is mounted. The function of the switch 422 and the cam wheel 460 will be described at a later point.

By reference to Fig. 17 it may be observed that the conductor 440 from the other side of the solenoid coil 386 is connected at its other end to a leaf spring contact member 465 disposed within a switch housing 466. The switch housing 466 (Figs. 1, 3 and 17) is secured by screws 468 to a bracket 469, the lower end of which is secured as by screws 471 to the chain guard 452. The switch 466 has therein a fixed contact bar 471 to which one end of a conductor 470 is connected, the other end of the conductor being connected to the conductor 312 extending from the vacuum switch 395 to the lead wire 313. The switch 466 is similar in construction to the switch 422 hereinafore described, and it embodies a plunger 472 of insulating material which is normally urged out-

wardly by the leaf spring contact member 465. The outer end of the plunger 472 engages an operating lever 473 which is pivoted on a stud 474 to the switch housing 476. The lower end 5 of the lever 473 rotatably mounts a cam follower 475. The cam follower 475 is adapted to engage the periphery of a cam wheel 476 keyed to the end of the shaft 182 adjacent the cam wheel 460. The cam wheel 476 has a raised portion or lobe 10 477 integral therewith which is adapted to intermittently open the switch 466 as will be more readily understood from a reading of the following circuit description.

Assuming the machine to be in repose and the 15 web of wrapping material to extend from the roll R (Fig. 3) to the feed rollers 184 and 185, and assuming also that no cakes have been deposited on the feed conveyor bars 93 and 94, the control system will be as shown in Fig. 17 of the drawings. Herein the line switch 314 is open, the motor 30 is deenergized, the switch 466 is normally closed and the switch 422 is normally open. The electromagnet 386 is deenergized with the result that contacts 410, 411, 412 and 413 are 20 separated. The pneumatically operated switch 395 is closed and the clutch control electromagnet 300 is deenergized.

The position of the switches 422 and 466 is controlled by the lobes 461 and 477 of the cams 25 carried by the cam shaft 182, and it is characteristic that the cam shaft 182 always stops in the position substantially as indicated in Fig. 17 and remains in that position when the machine is inactive. It follows, therefore, that the 30 circuit is as described hereinabove when the machine is at rest.

Upon closure of the switch 314, a circuit is 35 established from the power line through the conductor 31, the motor 30 and the return conductor 32. The motor is thereby energized with the result that power is transmitted through the pulley 35, the belt 36 and to the pulley 37 (Fig. 15) which, however, at this point rotates freely on the shaft 40 for the reason that the 40 dog clutch member 42 has not yet been engaged in driving relation. Upon closing the line switch 314 a circuit is also established to energize the electromagnet 386, which is in control of the time delay switch 405, this circuit being through conductors 317, 442 and 441 to the electromagnet 386 and thence through conductor 440 to one side of the normally closed switch 466, through conductor 470 and to the opposite side of the line. When the electromagnet 386 is energized 45 the Z-shaped control bar 393 is withdrawn from supporting contact under the insulating block 397, with the result that the spring 400 will become operative to open the contact points of the switch 405 under the control of the time delay device 306. It will be observed therefore that the contact points of switch 405 are normally open until 50 electromagnet 386 is deenergized, thereby permitting the tension spring 394 to act on the switch operating mechanism for closing the circuit thereat. This condition prevails upon opening 55 of the contact points of switch 466.

The shipper handle 260 is moved in a clockwise direction as viewed in Fig. 5 to raise the weight member 281 to the position shown in this 60 figure, the weight normally being in a lowered position while the machine is inoperative. The tension spring 290 in Fig. 14 urges the slide member 287 from left to right against the shaft 264 when the weight 281 is in a lowered position, and 65 consequently, when the weight member 281 is 70 75

raised, the tension spring 290 will urge the slide member 287 into engagement with the annular groove 286 on the shaft 264 and will also move the lever arm 292 out of engagement with the core 296 of the electromagnet 300, as shown in Fig. 14.

The sequence of movements just described will also result in movement of the brake shoe 294a from the position shown in Fig. 7 to the position shown in Fig. 6, thereby releasing its engagement with the hand wheel 51. As the shipper shaft 50 is moved from left to right in Fig. 15, the dog clutch member 43 is moved into engagement with the dog clutch member 42, thus transmitting power through the pulley 31 to the shaft 40 for rotation of the shaft in a clockwise direction as viewed in Figs. 2 and 4, or in a counterclockwise direction as viewed in Fig. 10. Rotation will then be transmitted to the shaft 55 through the pinion 53 on the shaft 40 and the gear 54 on the shaft 55 (Fig. 2), which in turn will transmit rotation to the forwardly and rearwardly extending shaft 60 (Fig. 10) through the miter gears 56 and 57, thus rotating the shaft 60 in a clockwise direction as viewed in Fig. 3. The shaft 60 transmits rotary motion to the shaft 65 through the miter gears 62 and 63.

By reference to Fig. 2 it will be noted that the sprocket wheel 66, mounted on the shaft 65 will transmit rotary motion to the shaft 71, 30 through the sprocket chain 67 and the sprocket wheel 70, thereby driving the conveyor chains 73-76, inclusive, as well as the chains 101.

It will be remembered that no cakes have yet been deposited on the conveyor bars 93 and 94, and therefore the cake sensing finger 163 is in its elevated position, and so long as this position is maintained the clutch finger 151 will remain out of engagement with the clutch tooth 156 through which motion is transmitted to the shaft 60. Consequently, the paper severing and delivering mechanism is inactive even though the cake conveying mechanism and the elevator mechanism is in operation. Assuming, therefore, that it is desired to wrap cakes in normal process, 45 the cakes on their supporting pallets D will be deposited on the conveyor bars 93 and 94, and such cakes will be moved from the loading end of the conveyor toward the wrapping zone as operation of the machine continues. As soon as a cake approaches the wrapping station, it will depress the cake sensing finger 163, thereby rocking its associated link about the pivot point 163a and thereby imparting such longitudinal movement to the operating rod 165 which will effectively withdraw the latch segment 166 from contact with the pin shoulder 171. When the pin 172 is rendered free to rise and fall with the normal rotation of the clutch pawl 151 as it rotates, the pawl actuating spring 153 will draw the tooth of the pawl into contact with the clutch tooth 156, thereby transmitting a rotary motion to the sprocket gear 147, in contact with which is disposed the sprocket chain 160. Rotary motion is thereby transmitted to the shaft 175 and through the intermediate gears (not shown) to the paper cutting and delivery mechanism.

It follows from the foregoing, therefore, that upon closure of the line switch 314 and consequent energization of the motor 30, the conveyor 70 mechanism and the cake elevating mechanism is rendered fully operative to perform its intended function. However, the paper cutting and delivery mechanism remains idle and will not come into operation until the power transmitting

mechanism between the shaft 60 and the paper cutting and delivery mechanism is rendered operative by contact between the cake sensing finger 163 and a cake overriding its position. As soon as the paper cutting and delivery mechanism has been rendered operative, wrapping sheets will be severed from the supply web and delivered to the wrapping station under guidance of the conveyor belts 135. As heretofore described, the paper sensing nozzle 352 is located in proximity to the wrapping station and within the line of movement of a severed wrapping sheet that is being properly fed into the wrapping station. The control system illustrated in Fig. 17 of the drawings is particularly designed for control under the influence of a wrapping sheet at the wrapping station. Consequently the sheet sensing nozzle 352 is the principal control instrumentality for the control system as will appear from a consideration of the further operation of the system.

So long as cakes are fed in normal sequence to the wrapping station, the cake sensing finger 163 will remain depressed and consequently the sheet severing and delivery mechanism will remain in operation. Upon arrival of a wrapping sheet at the wrapping station, a sheet sensing cycle is initiated, and so long as sheets are regularly presented in proper position at the wrapping station, normal operation of the machine continues. Thus, provision has been made for impressing an electrical sensing impulse on the control system in timed relation to the arrival of a wrapping sheet at the wrapping station. It will be remembered that the control instrumentalities are as described hereinabove, i. e. the switch 422 is normally open, the switch 466 is normally closed and the switch 305 is also normally closed. The closed condition of the switch 466 is effective to energize the electromagnet 386, thereby permitting the contact points of switch 415 to open. With the control system conditioned in this manner, the clutch and brake control electromagnet 300 remains deenergized. However, upon the approach of a wrapping sheet at the wrapping station, the raised portion 477 of the cam 476 rides into contact with the cam follower 475 and depresses the same. As the cam follower lever 473 is swung in a counterclockwise direction about its pivot 474, the switch operating pin 472 is pressed inwardly, thereby separating the points of the switch and breaking the circuit that normally energizes the electromagnet 386. When the electromagnet 386 is deenergized, the spring 394 will move the switch operating block 397 upwardly into the delay return mechanism 306, thereby depressing the switch operating bar 407 and closing the contacts 411, 412, 413 and 414. This conditions the switch 405 for the transmission of an energizing impulse to the electromagnet 300 upon closure of the switch 422 in the event no wrapping sheet is present at the wrapping station. Herein, however, it is assumed that wrapping sheets are being presented at the wrapping station in normal sequence, and so long as a wrapping sheet is in a position overlying nozzle 352, the switch mechanism 305 is disabled, thereby breaking the circuit to the main clutch and brake control electromagnet 300. This sequence of events follows from the following features of the control system.

The peripheral notch 380 of the cam disc 377 is effective to actuate the fluid pressure pump 346 once during each wrapping cycle. The pump 346 operates herein as a suction pump when the

17

cam follower 375 thereof drops into the cam notch 380. When the diaphragm 365 of the pump is elevated by movement of the operating arm 375 about its pivot 373, a negative pressure is impressed on the pneumatic system extending between the pump and the fluid pressure switch 305. So long as a wrapping sheet overlies the nozzle 352 at the wrapping station, the negative pressure will influence the diaphragm 334 of the switch 305 and pull the same downwardly, thereby opening the contacts 308, 309, 324 and 325 of the switch structure. It will be recalled that the switch 305 is in the circuit of the clutch and brake control magnet 300, and consequently if this switch is open, no energizing current will reach the magnet 300 and consequently machine operation will proceed in normal course.

The instrumentality for impressing the sensing impulses on the circuit of the magnet 300 is the lobe 461 of the cam which influences the switch 422. The lobe 461 is so designed and positioned as to render effective operation of the switch 422 immediately after the pneumatic impulse has been generated by the dropping of the cam follower 375 into the peripheral cam slot 380. When the lobe 461 rides in contact with the cam follower 457, the follower lever 454 is rotated in a clockwise direction about its pivot point 455, thereby pressing the switch operating rod 453 inwardly and closing the contact 444 of the switch 422. When this condition is achieved, an energizing impulse of momentary duration is impressed upon the circuit in which the brake and clutch magnet 300 is disposed. This circuit is by way of the conductors 317, 442 into the now closed switch point 444, through the conductor 420 into the now closed switch 405, through the conductor 302 into the electromagnet 300 and from there through the conductor 301 into the switch 305. As hereinbefore related, however, if a sheet of wrapping material is positioned over the sheet sensing nozzle 352, the negative pneumatic impulse generated by the fluid pressure pump 346 will permit depression of the diaphragm 334 of the pneumatic switch 305, thereby separating its contact points. When this condition prevails the circuit in which the electromagnet 300 is disposed will be incomplete and the magnet will therefore be not energized.

Let it be assumed now that a wrapping sheet has failed for any one of several reasons to arrive in proper position at the wrapping station, the nozzle 352 will therefore be open to the atmosphere, and when the fluid pressure pump 346 is operated by the presence of the cam slot 380, air will be drawn through the open nozzle 352 and the pneumatic impulse device will therefore have no effect on the pneumatic switch 305. In this event, the contacts 308, 309, 324 and 325 of the pneumatic switch 305 will remain closed under the influence of the spring 327. With the contacts closed, as described, the impulse that has been impressed on the control system by closure of the now closed sensing switch 422 will be through the electromagnet 300 as hereinbefore described, but the circuit will continue through the closed contacts of the pneumatic switch 305 to the opposite side of the line, through conductors 312, 313 through closed line switch 314. In this event, the electromagnet 300 will be energized, thereby drawing its armature 292 into contact with the magnet core 296. Movement of the armature 292 about its pivot point 293 will withdraw the latch plate 287 from its control position within the groove 286 on the face

75

18

of the rod 264. Upon the achievement of this condition, the weight 277 will fall to its lower position, thereby drawing the chain 262 downwardly with the result that the shipper bar 260 is rotated in a counterclockwise direction and carries with it the operating rod 252 (Figs. 5 and 15) which influences the operative position of the main transmission clutch and the brake shoe. Specifically, as the rod 252 is rotated in a counterclockwise direction, the clutch shaft 50 is moved laterally in a right to left direction as viewed in Fig. 15, thereby separating the complementary clutch members 42 and 43, which separation effectively disconnects the wrapping machine mechanism from its power source. At the same time, oscillation of the shaft 252 in its bearing brackets 254 will be effective to rock the brake member 249 in a counterclockwise direction to bring the brake shoe 249a into contact with the hand wheel 51. This contact will be effective to bring the entire mechanism to a prompt halt.

It will be recalled that one of the objects of the invention is to provide means whereby the cake elevating mechanism may continue to operate for a predetermined length of time for elevating the cake to a position above the point at which it normally engages the wrapping material and to thereby position the cake where it will be accessible for removal after the machine has been stopped in case there has been a failure in wrapping sheet delivery. To the end that this objective is implemented, there has been established a relation between the cam 121 from which the cake elevating arm 115 is operated and the lobe 461 of the cam which operates the switch 422. These cams are so designed and mounted that the cake transfer mechanism, including the elevator arm 115, will approach its ultimate transfer position at the wrapping station before the lobe 461 of the switch actuating cam comes into contact with the cam follower 457 to thereby impress a sensing impulse on the circuit which includes the electromagnetic device 300 and the pneumatic switch 305. It follows, therefore, that if a cake is present under the wrapping station, even though no wrapping sheet is present therein, the transfer mechanism will continue to operate and the elevating arm 115 will elevate the cake to nearly its ultimate position in the wrapping station before the switch 422 is closed to energize the electromagnet circuit. As a consequence, the electromagnet 308 will come into operation if no sheet of wrapping material is present over the sensing nozzle 352 and disable the power transmission device between the source of power and the drive shaft of the wrapping machine as the transfer arm 115 approaches its ultimate position. Prompt stoppage of the machine, of course, follows because of the provision of the brake device operative on the hand wheel 51.

It will follow from the foregoing, therefore, that there has been provided herein a wrapping machine control mechanism which is effective to control sheet cutting and delivery mechanism under the influence of normal feed of cakes by a conveyor mechanism into a wrapping station. Particularly, it is to be observed that the sheet severing and delivery mechanism is energized only when a cake is moved into the wrapping station. This function is effective to avoid the delivery of wrapping sheets into the wrapping station when no cakes are present. Coggage in the wrapping station by wrapping sheets and

consequent waste of such sheets is thereby avoided. Furthermore, it is apparent from the foregoing that there has been provided herein a control system for wrapping machines, wherein provision is made to avoid the delivery of a cake into the wrapping station at such times that wrapping sheets are absent or improperly positioned at such station to receive the cake to be wrapped. This function effectively avoids the passage of cakes into the folding and sealing stations of the machine when no wrapping sheet is present at the wrapping station, and consequently avoids the passage of unwrapped cakes into subsequent stages of the packaging operation.

The control system forming the substance of the invention has been shown as applied to a particular wrapping machine of conventional structure, and it has been made clear hereinbefore that this particular wrapping machine has been selected merely for the purpose of illustration and that the control system may be applied to any wrapping machine of its general type or other machines of similar structure. Furthermore, the control system has been disclosed in a single embodiment and it is manifest, however, that changes may be made in this system within the skill of one in the art without departing from the spirit of the invention as defined in the following claims.

What is claimed is:

1. In a wrapping machine having a conveyor for transporting articles to a wrapping station, a drive means for said conveyor, means for delivering separate sheets of wrapping material to the wrapping station in timed relation to the transfer of articles to the wrapping station, and a source of power; a stop motion system comprising a power transmission clutch between the drive mechanism and the power source, an electromagnet device for controlling said clutch, a normally closed pneumatic switch, a normally open circuit connecting said electromagnetic device and said switch with a power source, an air pump for impressing pressure changes on said switch, wrapping sheet sensing means in the path of a wrapping sheet as it is being delivered to said wrapping station responsive to such sheet for rendering effective the influence of said air pump to open said switch, means operative concurrent with the delivery of an article to said wrapping station by said conveyor for impressing a momentary electrical impulse on said circuit following operation of said pump, and means operative during the operation of said pump for closing said normally open circuit.

2. In a wrapping machine having a conveyor for transporting articles to a wrapping station, a drive means for said conveyor, means for delivering separate sheets of wrapping material to the wrapping station in timed relation to the transfer of articles to the wrapping station, and a source of power; a stop motion system comprising a power transmission clutch between the drive mechanism and the power source, an electromagnetic device for controlling said clutch, a pneumatic switch, a normally open circuit connecting said electromagnetic device and said switch with a power source, an air pump for impressing pressure changes on said switch, wrapping sheet sensing means in the path of a wrapping sheet as it is being delivered to said wrapping station responsive to such sheet for venting said pump to the atmosphere in the absence of a sheet effective to close said switch, a cam mechanism for intermittently operating said pump for exhausting said conduit thereby opening said switch, means including a normally open circuit for impressing a momentary electrical im-

operative concurrent with the delivery of an article to said wrapping station by said conveyor for impressing a momentary electrical impulse on said circuit following operation of said pump, and means operative during the operation of said pump for closing said normally open circuit.

3. In a wrapping machine having a conveyor for transporting articles to a wrapping station, a drive means for said conveyor, means for delivering separate sheets of wrapping material to the wrapping station in timed relation to the transfer of articles to the wrapping station, and a source of power; a stop motion system comprising a power transmission clutch between the drive mechanism and the power source, an electromagnetic device for controlling said clutch, a normally closed pneumatic switch, a normally open circuit connecting said electromagnetic device and said switch with a power source, an air pump for impressing pressure changes on said switch, wrapping sheet sensing means in the path of a wrapping sheet as it is being delivered to said wrapping station responsive to such sheet for rendering effective the influence of said air pump to open said switch, a rotary cam operative concurrent with the delivery of an article to said wrapping station by said conveyor for impressing a momentary electrical impulse on said circuit following operation of said pump, and a second rotary cam operative during the operation of said pump for closing said normally open circuit.

4. In a wrapping machine having a conveyor for transporting articles to a wrapping station, a drive means for said conveyor, means for delivering separate sheets of wrapping material to the wrapping station in timed relation to the transfer of articles to the wrapping station, and a source of power; a stop motion system comprising a power transmission clutch between the drive mechanism and the power source, an electromagnetic device for controlling said clutch, a pneumatic switch, a normally open circuit connecting said electromagnetic device and said switch with a power source, an air pump for impressing pressure changes on said switch, wrapping sheet sensing means in the path of a wrapping sheet as it is being delivered to said wrapping station, responsive to such sheet for venting said pump to the atmosphere in the absence of a sheet effective to close said switch, a rotary cam operative concurrent with the delivery of an article to said wrapping station by said conveyor for impressing a momentary electrical impulse on said circuit following operation of said pump, and a second rotary cam operative during the operation of said pump for closing said normally open circuit.

5. In a wrapping machine having a conveyor for transporting articles to a wrapping station, a drive means for said conveyor, means for delivering separate sheets of wrapping material to the wrapping station in timed relation to the transfer of articles to the wrapping station, and a source of power; a stop motion system comprising a power transmission clutch between the drive mechanism and the power source, an electromagnetic device for controlling said clutch, a normally closed fluid pressure switch in the circuit of said electromagnetic device, a fluid pressure pump, a conduit connecting said pump and said switch, a cam mechanism for intermittently operating said pump for exhausting said conduit thereby opening said switch, means including a normally open circuit for impressing a momentary electrical im-

21

pulse on the circuit including said switch and said electromagnetic device following operation of said pump, a cam operative concurrent with the delivery of an article to said wrapping station to render said impulse impressing means operative, a vent for said conduit in the path of a wrapping sheet as it is being delivered to said wrapping station, whereby in the absence of a sheet over said vent the fluid pressure switch will remain closed to permit operating current to energize said electromagnetic device, and means operative during the operation of said pump for closing said normally open circuit.
